LOCK WASHER

Frank W. England, Chicago, Ill., assignor to Illinois Tool Works, Chicago, Ill., a corporation of Illinois

Application August 8, 1935, Serial No. 35,257

15 Claims. (Cl. 151—35)

My invention relates generally to lock washers and methods of producing them, and particularly to lock washers of the type having overlapping portions which present locking or work engaging edges.

It is an object of my invention to produce a lock washer of the above mentioned overlapping type in a manner which reduces to a minimum the necessity of distorting washer stock.

10 To this end, my invention contemplates a new and improved method whereby a washer blank is provided with a plurality of marginal slits, and portions of the stock thus severed are then shifted inwardly so as to prevent overlapping stock portions.

15 A further object of my invention is to provide a new and improved overlapping type of washer having both inner and outer work engaging teeth.

Still another object of my invention is to pro-

20 vide an improved method of making lock washers, which contemplates the provision of an annular washer blank having irregular inner and outer peripheries, and subsequently subjecting portions of these peripheries to a shifting operation so as 25 to produce an annular type lock washer having work engaging teeth projecting on opposite sides of the medial plane of the washer.

25 The foregoing and numerous other objects and advantages will be more apparent from the following detailed description when considered in connection with the accompanying drawing, wherein—

30 Figure 1 is a plan view of a lock washer blank formed in accordance with the teachings of my invention, namely, with irregular inner and outer peripheries;

35 Figure 2 discloses said blank after the peripheral portions thereof have been so shifted as to produce overlapping sections, and presenting work engaging edges positioned on opposite sides of the medial plane of the washer;

40 Figure 3 is an enlarged elevational view of the edge of the washer shown in Figure 2 to more clearly illustrate the overlapping washer sections;

45 Figure 4 is a modified washer blank also constructed in accordance with the teachings of my invention;

50 Figure 5 discloses the blank of Figure 4 after the inner and outer severed sections have been shifted so as to produce the overlapping effect; and

55 Figure 6 is an enlarged view of the edge of the washer shown in Figure 5 to more clearly illustrate the overlapping washer sections.

55 Referring now to the drawing more in detail

wherein like numerals have been employed to designate similar parts throughout the various figures, it will be seen that one embodiment of my invention contemplates an overlapping prong washer of the type shown in Figure 2. This 5 washer is designated generally by the numeral 10 and comprises a plurality of outer overlapping sections 12 and a plurality of inner overlapping sections 14. The overlapping sections 12 produce oppositely disposed work engaging 10 edges or portions 16 and 18, while the inner overlapping sections 14 present work engaging edges or portions 20 and 22.

The washer is preferably produced by forming a 15 blank of the type shown in Figure 1 from suitable flat spring stock. It will be noted that this blank is formed with irregular inner and outer peripheries, namely, peripheries having teeth projecting inwardly and outwardly.

Outer slits 24 and inner slits 26 are provided 20 to facilitate the subsequent overlapping operation. Following the formation of the blank shown in Figure 1, the ratchetlike teeth along the inner margin are flexed downwardly and the ratchetlike teeth along the outer margin are flexed upwardly a sufficient distance to clear the adjacent portions of stock, which adjacent portions are also flexed laterally to facilitate subsequent overlapping. Then the outer teeth are shifted radially inward and the inner teeth are 25 shifted radially outward so as to produce the overlapping sections 12 and 14, respectively, as shown in Figure 2. I prefer to form the slits 24 and 26 tangentially to an imaginary circle, the center of which constitutes the center of the 30 washer. Thus, when the inner and outer teeth are shifted to produce the overlapping effect, the 35 amount of strain or distortion experienced by the washer stock is held to a minimum. It will also be noted that in practicing the method just described, only very small sections of the washer need be shifted to produce the overlapping effect.

This is to be distinguished from methods of producing overlapping prong lock washers, wherein substantially the entire washer stock, during the 40 overlapping process, is subjected to strains and 45 stresses.

In Figures 4 to 6, inclusive, I have disclosed 50 a modified washer arrangement designated generally in Figure 5 by the numeral 10a. This washer is provided along the outer margin with overlapping locking sections 12a, and along the inner margin with overlapping locking sections 14a. The locking sections 12a comprise a series 55 of prongs or locking elements 16a bent upwardly,

as viewed in Figure 5, and a plurality of locking elements 18a, which are superimposed by the elements 16a. Likewise, the inner locking sections 14a comprise a plurality of locking elements 20a, which superimpose or overlap companion locking elements 22a. The elements or prongs 22a are flexed downwardly out of the medial plane of the washer in the same way that the prongs or locking elements 16a are flexed upwardly.

In producing the washer 10a, a blank is first formed as shown in Figure 4. This blank, like the blank disclosed in Figure 1, is provided with irregular peripheries and a plurality of outer 15 tangential slits 24a and a plurality of inner tangential slits 26a. The prong or locking element 16a presented to one side of the slit 24a is then bent or warped upwardly, as viewed in Figure 4, and the prong or locking element 22a is bent 20 downwardly. The elements 16a are then shifted radially inward and the elements 22a shifted radially outward to produce the locking device shown in Figure 5. It will be noted that the peripheral edges of the prongs or locking elements 16a and the inner peripheral edges of the locking elements 22a are preferably arcuate, so that, when these elements are shifted to their 25 final position, a lock washer is presented having circular inner and outer peripheries.

From the foregoing, it will be apparent that the invention contemplates the provision of overlapping prong lock washers, which may be produced by the practice of very simple steps without the inherent danger of subjecting the washer stock to permanent injury. In other words, the overlapping is produced by subjecting small sections of the washer stock to slight distortion. Furthermore, in the production of my improved washer, only one of the prong sections need be 30 shifted, the other or companion section remaining stationary. For example, in Figure 5 the outer locking elements 18a remain fixed or stationary, while the locking elements or prongs 16a are shifted into superimposing relation. 35 This is to be distinguished from methods of producing overlapping prong lock washers where both of the elements, constituting the overlapping portion, are shifted. In other words, my invention contemplates the method of producing 40 lock washers of the overlapping type, wherein tangential prongs are shifted radially or transversely with respect to the fixed portion of the washer stock to produce the overlapping effect. Furthermore, the invention contemplates a 45 method wherein a washer blank is first produced having a series of ratchetlike teeth provided along at least one of the margins, and these teeth are subsequently shifted to produce the overlapping 50 effect. In practicing my improved method, the original consistency of the washer stock is maintained.

It is correct to state that the lock washers disclosed herein, which are comprised of spring 55 stock, include a series of body portions and a plurality of teeth such as the ratchetlike teeth 16 of Figures 1 to 3, inclusive, each of which is bent in overlapping relation with one of the body portions along at least one margin thereof. 60 The lock washer shown in Figures 1 to 3, inclusive, includes serrations or slits 24 and 26 which extend substantially half way across the radial width of the washer stock. In Figures 4 and 5, however, the tangential arrangement of the slits 70 75 24a and 26a do not traverse the radial width

of the washer stock to such a great extent. In any event the series of body portions annularly disposed with respect to the washer axis are adapted to be overlapped by the adjacently positioned prongs or teeth.

While I have disclosed specific forms of washers capable of being produced by the practice of my improved method, obviously the invention is not limited to these forms, but contemplates other modifications and changes coming within the 10 scope of the appended claims.

Having thus described my invention, what I claim as new and desire to secure by Letters Patent is:

1. A lock washer of spring stock including a 15 series of body portions and a plurality of ratchet-like teeth each positioned in overlapping relation with one of the body portions along at least one margin thereof.

2. A lock washer of spring stock including a 20 series of body portions and a plurality of ratchet-like teeth arranged in overlapping relation with one of the body portions along the inner and outer margins thereof.

3. A lock washer of spring stock including a 25 body and a plurality of marginal prongs arranged in overlapping relation with said body, each of said prongs having an edge tangential with respect to a circle concentric with the washer axis.

4. A lock washer of spring stock including a 30 body and a plurality of marginal prongs arranged in overlapping relation with said body, along the inner and outer margins thereof, each of said prongs having an edge tangential with respect to a circle concentric with the washer.

5. A lock washer of spring stock including a 35 series of body portions and a plurality of marginal prongs overlapping sections of the body, said prongs presenting work engaging edges positioned out of the medial plane of the body.

6. A lock washer of spring stock including a 40 plurality of inner and outer annularly disposed prongs, certain of said prongs having work engaging edges positioned on one side of the medial plane of the washer and other prongs presenting edges on the opposite side of said medial plane, each prong overlapping a section of washer stock 45 different in shape from said prongs.

7. A lock washer of spring stock including a 50 plurality of marginal prongs tangentially disposed with respect to a circle concentric with the washer axis and arranged in overlapping relation with respect to the washer stock along at least one margin thereof, edges of said prongs being so 55 disposed as to present arcuate inner and outer washer peripheries when positioned in overlapping relation.

8. The method of producing lock washers which 60 consists in forming a body of spring stock, forming ratchetlike teeth along at least one periphery, and then shifting said ratchetlike teeth radially of the body into overlapping relation with the adjacent sections of the body.

9. The method of producing lock washers 65 which consists in forming a body of spring stock, forming ratchetlike teeth along inner and outer margins thereof, and then shifting said ratchetlike teeth radially of the body into overlapping relation with the adjacent sections of the body.

10. The method of producing lock washers 70 which includes the steps of forming a plurality of prongs along at least one margin of a body of spring stock tangentially disposed with respect to the washer stock, and then shifting said prongs 75

- into overlapping relation with the adjacent section of the washer body.
11. The method of producing lock washers which includes the steps of forming a plurality of tangential prongs along at least one margin thereof, said prongs being tangentially disposed with respect to the washer stock, axially shifting the free extremities of said prongs out of the plane of the washer body, and shifting said free extremities into overlapping relation with said adjacent sections of the body.
12. A lock washer comprising a body, and a plurality of marginal teeth, a portion of each of said teeth overlapping a portion of the body.
13. A lock washer comprising a body and a plurality of marginal teeth, each of said teeth

being bent toward and overlapping a portion of the body.

14. A lock washer comprising a body, and a plurality of marginal teeth, said teeth being divided from the body by cuts on lines tangential to a circle concentric with the body, and each tooth being bent toward the body and a portion thereof overlapping a portion of the body.

15. A lock washer comprising a body, and a plurality of marginal teeth, said teeth being divided from the body by cuts on lines tangential to a circle concentric with the body, and each tooth being bent out of the plane of the body and toward the body, a portion of each tooth overlapping a portion of the body.
